UNITED STATES PATENT OFFICE.

OWEN L. HARRISON, OF COLETA, ILLINOIS.

STOVE.

Application filed May 7, 1924. Serial No. 711,670.

To all whom it may concern:

Be it known that I, OWEN L. HARRISON, a citizen of the United States, and a resident of Coleta, in the county of Whiteside and State of Illinois, have invented certain new and useful Improvements in Stoves; and I do hereby declare the following to be a full, clear, and exact description of the invention, such as will enable others skilled in the art to which it appertains to make and use the same.

This invention relates to stoves which use oil or gas as fuel and one object is to provide a novel construction whereby the heat from the burner may be quickly distributed to all portions of the top plate. Another object is to provide means whereby the distribution of the heat may be easily and effectually controlled, and yet another object is to provide means whereby the burner will be firmly supported in operative relation to the heat-distributing elements but may be easily withdrawn when cleaning, wick-trimming or other operations, incidental to use, are to be performed. Other objects will appear in the course of the following description, and the invention resides in certain novel features which will be hereinafter fully described and particularly pointed out.

In the annexed drawings, Figure 1 is a side elevation, partly broken away and partly in section, of a stove embodying the invention;

Figure 2 is an end view of the same;

Figure 3 is a perspective view of the top plate;

Figure 4 is a perspective view of the pan or support for the top plate;

Fig. 5 is a detail perspective view of the burner support;

Fig. 6 is a detail perspective view of the bracket which carries the burner support;

Fig. 7 is a detail perspective view of the lever which effects adjustment of the burner;

Fig. 8 is an enlarged elevation of the guide for the burner assembly.

Figure 9 is a perspective view showing a top plate and damper construction different in some particulars from the form shown in Figures 1 to 4;

Figure 10 is an end elevation of the top plate structure shown in Figure 9;

Figure 11 is a detail view of a portion of

the blank from which a top plate unit may be formed;

Figure 12 is a detail section of a portion of the top plate structure shown in Figure 9;

Figure 13 is detail perspective view of the central plate shown in Fig. 9;

Figure 14 is a sectional elevation showing a chimney mounting differing from that shown in the other figures.

The stove structure includes a supporting frame consisting of legs 1, preferably of angle bars, connected by cross bars or braces 2 and side rails or braces 3. Upon this frame is carried a pan 4 which may be constructed of sheet metal and has hollow side walls 5 adapted to rest on the rails 3 and connected by the end walls 6. The end walls are lower than the side walls and are provided at their upper edges with inwardly projecting flanges or webs 7. Above the flanges or webs 7, dampers 8 are mounted between the ends of the side walls and consist preferably of rectangular plates of dimensions corresponding to the space between the side walls and above an end wall. At the ends of the dampers are journals 9 rotatably engaged through the side walls, and a handle 10 is secured upon one journal of each damper whereby to adjust the damper. In the bottom 11 of the pan, preferably at the center, is an opening 12 about which is provided a collar or ring 13 the diameter of which diminishes upwardly, and at opposite sides of said opening transverse plates or partitions 14 are secured to the bottom and side walls of the pan. These partitions converge upwardly and rise to the plane of the ledges 7, and between said partitions, at opposite sides of the opening 12, are longitudinally extending partitions 15. Between the partitions 14 and the end walls and between the partitions 15 and the side walls, the bottom of the pan is covered with asbestos or other heat-resisting material so that radiation downwardly from the top plate and pendant elements thereon will be counteracted.

The top plate shown in Figures 1 to 4 consists of a flat thin metal plate 16 of proper dimensions to rest on the upper edges of the side walls 5 and extend from end to end thereof. Through the plate, preferably at its center, is an opening 17, which is normally closed by a lid 18, and on the under-

side of the plate are a plurality of parallel thin longitudinal heat-conducting elements or fins 19 which terminate short of the edges of the plate, leaving marginal portions to rest upon the side walls of the pan and accommodate the dampers. The function of these elements 19 is to transmit heat to the plate 16 and they should, therefore, be very thin and sufficiently numerous to extend over approximately the entire surface of the plate. As a convenient method of permanently securing the fins in place, they are provided with basal flanges 20 constructed with openings therein to receive studs formed on the plate, the studs being upset, in the manner of a rivet, against the flange. Two adjacent fins may have the same basal flange thereby constituting a channel member, as shown in Figure 3.

20 The burner 21 is equipped with a chimney 22 of cylindrical form with a tapered upper end 23 fitting closely within the ring 13 so that there can be no flow of air into the pan around the outside of the chimney 25 which, obviously, would have a cooling effect and cause the consumption of an excessive quantity of fuel. The burner is carried by an arm 24 extending from a plate 25 which is fixed to the lower end of a sleeve 26 slidably mounted on a post 27 which is secured at its upper end to a cross bar 28 and at its lower end in a bracket 29. The cross bar 28 is secured between the rails 3 of the main supporting frame and the bracket 29 is secured to a cross bar 2 carried by the legs 1. On the sleeve 26 is a boss 31 to which is pivoted the short arm of an angle lever 32 which has the free end of its longer arm turned laterally to form a handle 33. To said lever, at the bend thereof, is pivoted the lower end of a link 34 which is freely suspended at its upper end on the cross beam 28. The burner may be connected to the arm 24 in any preferred manner, and I have shown a lug 35 depending from the base of the burner and connected to the arm 24 by a screw 36. When the lever is in its lowered position, the connection with the link 34 is past the dead center and the lever is thereby held down. When the lever is swung to raised position, the end of the link is carried outwardly so that the sleeve 26 with the arm 24 and the burner will be lowered, the chimney being withdrawn from the ring 13 so that it may be removed from the burner or swung over its side to permit lighting of the burner, cleaning, or trimming of the wick, if the fuel be of such kind as to require use of a wick.

60 The fuel may be supplied from a tank or reservoir 37 which is raised or lowered with the burner in order to prevent flooding of the burner when the latter is lowered, the tank being preferably of the vacuum feed type. A feed pipe 38 connects the bottom

of the tank with the burner, and a tank-holder 39 is fitted on the pipe to support the tank. The plate 25 extends past the end of the sleeve 26 and is provided in its upper side with a groove 40 extending parallel with the arm 24 to receive and support the feed pipe, a clamping plate 41 of counterpart construction being secured upon the plate 25 over the pipe to hold the pipe in place, while a loop 42, secured on the cross bar 30 and passing over the pipe, guides the burner assembly in its vertical movements and maintains its alignment.

When the top plate 16 is in place, the fins or heat conductors 19 extend to the heat-resisting body in the pan and the heat rising from the burner through the distributing chamber defined by the partitions 14 and 15 must pass out between the fins or elements 19, and, as these elements are very thin and numerous, they soon become heated and transfer the heat to the plate. The burner is, of course, equipped with a wick-raiser or other flame-regulating device (not shown). If the flame be large and both dampers open, the whole top soon becomes hot enough for cooking; if one damper be fully closed and the other wide open, with a moderate flame, the closed end soon becomes hot enough for making coffee or tea; if both dampers be closed and the stove lid removed, an oven may be set over the opening 17 and baking accomplished. Various adjustments of the dampers may be effected according to the conditions of use and the work to be done. As the burner is located preferably at the center of the stove, the rising heat is naturally divided between the ends of the top plate, and as the fins are straight and parallel the heat travels without deviation and the entire top plate is quickly and evenly heated.

In Figures 9 to 13 I have illustrated a form of the invention which embodies a top plate construction different from that previously described. Referring particularly to Figure 11, 43 designates a blank of thin sheet metal of rectangular outline and preferably, though not necessarily, having a central longitudinal flat thickened portion 44. This blank is rolled or otherwise bent to form a hollow I-bar 45 and a plurality of the I-bars are assembled side by side, as shown in Figure 10, openings 46 being formed through the webs of the bars and arranged in alignment. Side plates 47 are disposed against the sides of the outermost bars and clamping rods 48 are inserted through the openings 46 and corresponding openings in the side plates whereby to secure the bars firmly together. In this embodiment of the invention, the tops of the I-bars form the top plate and the assembled I-bars are disposed in the pan so as to rest on the webs or flanges 7 of the end walls 130

and on the edges of the partitions 14, the pan being of the same construction as before described except as to features which will be presently mentioned. The bottom webs 5 of the I-bars are removed between the partitions 14 of the pan so that the heat from the distributing chamber may enter the bars and flow toward the ends of the same. Those I-bars which would normally extend over 10 the opening 12 in the pan are reduced in length by being cut away at their centers through a distance equal to the diameter of said opening. Within the open area thus exposed is fitted a plate 49 having a central 15 round opening 50 therethrough and provided at its ends with supporting lugs 51 adapted to enter the open ends of the heads of the shortened I-bars and thereby retain the plate in place. The usual stove lid is 20 fitted to the opening 50 which is round because experience has shown that with the circular form the lid is less apt to fall through the opening.

The rocking dampers previously described 25 cannot be accommodated with the I-bar construction of top plate, and I, therefore, employ the vertically sliding dampers 52 which are mounted against the outer sides of the 30 end walls of the pan, and, in their highest positions, cover the ends of the I-bars. These 35 damper plates are provided near their ends with vertical slots 53 receiving lugs 54 projecting from the end walls of the pan and forming guides for the dampers and bearings for the damper-adjusting shaft 55 which shaft is equipped at one end with an 40 operating head or handle 56 and between its ends with pinions 57 meshing with racks 58 on the dampers. By rotating the shaft in one or the other direction, the damper will 45 obviously be raised or lowered to wholly or partly cover or uncover the ends of the I-bars. It is to be understood that the term I-bars is used for convenience and not as a 50 limitation as the bars may be of other cross-sectional forms, provided they are hollow and the sides of adjacent bars are out of contact except at the top and bottom.

In the form shown in Figure 14, the 55 burner is supported in a fixed position and the chimney comprises a lower section 59 fitted to the burner and an upper section 60 mounted telescopically around the lower section and having its upper end tapered, as at 60 31, to fit closely within the collar or ring 13. The upper section is formed with two or more bayonet slots 62 in its wall in which are engaged correspondingly located studs 63 on the lower section. When the studs lie in the circumferentially extending 65 branches of the slots, the upper section of the chimney will be held in its raised position and, to effect a close engagement between the chimney and the pan, said branches of the slots may be inclined so as

to have a cam action on the studs. By turning the upper chimney section, the vertical branches of the slots will be brought into engagement with the studs and the section then lowered. Reverse movement, of course, 70 will raise the chimney section and secure it in the raised position. To facilitate manipulation of the upper movable chimney section, ears or handles 64, of any preferred form, may be provided thereon. 75

Having fully described my invention what I claim as new and desire to secure by Letters Patent, is:—

1. A stove comprising a pan containing a 80 heat-resisting body, and a central heat-distributing chamber, a burner in said chamber, a top, heat-conducting elements on the under side of the top in communication with the burner, and dampers at the ends of the pan to cover or uncover the ends of the heat-conducting elements. 85

2. A stove comprising a pan having an 90 opening through its bottom, a burner fitted to said opening, partitions in the pan at opposite sides of said opening, a heat-resisting body in the pan between said partitions and the ends of the pan, a top resting on the pan and including heat-conducting elements extending downwardly to the heat-resisting body and open to the burner, and dampers 95 at the ends of the pan controlling the draft along the heat-conducting elements.

3. A stove comprising a pan having an 100 opening through its bottom, a top including heat-conducting elements, a burner fitted to the opening in the pan, and means for moving the burner into or out of operative relation to the opening. 105

4. A stove comprising a pan having an 110 opening through its bottom, a top including heat-conducting elements, a burner disposed below the opening in the pan, a tank supplying the burner, and means for moving the tank and the burner simultaneously whereby to position the burner relative to the opening in the bottom of the pan. 115

5. A stove comprising a supporting frame, a pan on said frame, a top on the pan, a post on the frame, an arm mounted slidably on the post, a burner carried by said arm, and means acting on said arm to raise and lower the same and thereby move the burner into or out of operative relation to the pan and the top. 120

6. A stove comprising a main frame, a post thereon, a pan carried by the frame, a top on the pan, a sleeve slidably mounted on the post, a plate carried by the lower end of the post, a burner carried by said plate, a tank, a feed pipe connecting the tank and the burner, means for clamping the pipe to the plate, and means for raising and lowering the sleeve whereby to move the burner into or out of operative relation to the pan and the top. 130

7. A stove comprising a pan having an opening through its bottom, a burner fitted to said opening, and a plurality of hollow thin I-bars supported in the top of the pan side by side and open to the burner.

8. A stove comprising a pan having an opening through its bottom, a heat-generator cooperating with the opening in the bottom of the pan, a distributing chamber in the pan surrounding said opening, a top plate supported upon the pan, and a plurality of heat-conducting elements intimately united with the under side of the top plate extending at an angle to the distributing chamber and open to said chamber, said elements being interrupted immediately over the opening in the bottom of the pan.

9. A stove comprising a pan having an opening through its bottom and a tapered collar around said opening, a burner below said opening, and a chimney for the burner having a tapered upper end fitted to said collar and movable into and out of the same.

10. A stove comprising a pan having an opening in its bottom, partitions extending between the side walls of the pan at opposite sides of said opening and defining with said walls a heat-distributing chamber, a burner

fitted to the opening in the bottom of the pan, a top plate supported by the pan over the distributing chamber, and heat-conducting elements intimately united with the under side of the top plate and extending from the distributing chamber to the ends of the top plate.

11. A stove comprising a pan having a central heat-distributing chamber and an opening in the bottom of said chamber, a burner fitted to the opening in the bottom of the heat-distributing chamber, a heat-resisting body extending from the heat-distributing chamber to the ends of the pan, a top plate supported by the pan and extending over the distributing chamber, and a plurality of thin heat-conducting elements intimately united with the under side of the top plate extending between the heat-distributing chamber and the ends of the top plate and resting on the heat-resisting body.

In testimony whereof, I have signed this specification in the presence of two subscribing witnesses.

OWEN L. HARRISON.
